US00D898037S

(12) **United States Design Patent** (10) Patent No.: **US D898,037 S**
(45) Date of Patent: ** Oct. 6, 2020

(54) **TABLET COMPUTER**

(71) Applicant: **Lenovo (Beijing) Co., Ltd.**, Beijing (CN)

(72) Inventor: **Run Yang**, Beijing (CN)

(73) Assignee: **Lenovo (Beijing) Co., Ltd.**, Beijing (CN)

(**) Term: **15 Years**

(21) Appl. No.: **35/506,377**

(22) Filed: **Dec. 11, 2018**

(80) **Hague Agreement Data**

Int. Filing Date: **Dec. 11, 2018**

Int. Reg. No.: **DM/200251**

Int. Reg. Date: **Dec. 11, 2018**

Int. Reg. Pub. Date: **Mar. 8, 2019**

(30) **Foreign Application Priority Data**

Jun. 11, 2018 (CN) 2018 3 0293677
